UNITED STATES PATENT OFFICE.

HARRY W. THOMPSON, OF PHILADELPHIA, PENNSYLVANIA, ASSIGNOR OF ONE-HALF TO WILLIAM M. FINKBEINER AND ONE-FOURTH TO LOUIS FREELING, BOTH OF PHILADELPHIA, PENNSYLVANIA.

SKIN-STRETCHING FRAME.

1,358,183.

Specification of Letters Patent.

Patented Nov. 9, 1920.

Application filed August 2, 1919. Serial No. 314,834.

To all whom it may concern:

Be it known that I, HARRY W. THOMPSON, a citizen of the United States, residing at Philadelphia, in the county of Philadelphia and State of Pennsylvania, have invented certain new and useful Improvements in Skin-Stretching Frames, of which the following is a specification.

One object of my invention is to provide an improved skin stretching frame which can be suspended in an upright position so as to enable the parts to be readily moved to stretch skins placed thereon.

Another object is to make my improved frame of a simple and durable construction and so that the movable parts can be securely held in position to retain the skin in an even stretched position.

These objects, and other advantageous ends which will be described hereinafter, I attain in the following manner, reference being had to the accompanying drawings in which—

Figure 1 is a front elevation of my improved frame showing thereon a skin in stretched condition,

Fig. 2 is a top plan view of Fig. 1,

Fig. 3 is a rear elevation of Fig. 1,

Fig. 4 is an end view of Fig. 3,

Fig. 5 is a sectional elevation taken on the line 5—5 of Fig. 1,

Fig. 6 is a perspective view of certain of the elements of my improved frame, and

Fig. 7 is a perspective view of my improved frame.

Referring to the drawings, my improved frame includes two uprights 8 and 9. Each of these uprights is made up of front and rear strips 10 and 11 which are spaced apart between their ends by blocks 12 and are joined together at their tops and bottoms by transverse upper and lower beams 13 and 14. Each of the beams 13 and 14 is made up of front and rear strips 15 and 16 which are spaced apart between their ends by blocks 17. The strips 15 of the upper and lower beams extend between and are joined to the strips 10 and 11 of the uprights 8 and 9. The strip 15 of the beam 13 has end portions 18 which extend beyond the uprights 8 and 9 and provide means whereby the frame can be suspended in an upright position by any suitable overhead means

(not illustrated). Each of the beams 13 and 14 have two rows of holes 19 and 20; 55 the holes being arranged in staggered formation and so that the holes in the strips 15 are directly in register with the holes in the strips 16 so that pins 21 can be inserted through any of the holes so as to extend 60 across the space 22 between the strips 15 and 16 in each of the beams 13 and 14.

In like manner the strips 10 and 11 of each of the uprights 8 and 9 have two rows of holes 23 and 24; said holes being arranged 65 in staggered formation; the holes of the strips 10 being in register with the holes in the strips 11 so that pins 25 can be inserted therethrough and extend across the space 26 between the front and rear strips 10 and 11. A board 27, which will hereinafter be termed a neck board, has its opposite ends 28 slidably vertically in the spaces 26 below the blocks 12. A second board 29 has its opposite ends 30 secured within the spaces 70 26 above the blocks 12 and directly below the upper beam 13, said board being hereafter termed the belly board.

Two upright shank boards 31 and 32 have their upper and lower ends respectively 80 slidably within the spaces 22 at opposite sides of the blocks 17. These shank boards are normally held from falling through the spaces 22 by the provision of stop blocks 33 which slidably rest upon the upper edges of 85 the strips 16 of the lower beam 14. The shank boards 31 are each provided with shank bay extensions 34; the front surfaces 35 being flush or in the same plane with the front surface 36 of the neck board 27 and 90 belly board 29.

By the above arrangement it will be noted that the shank boards are slidable transversely to the direction in which the neck board is slidable and that the shank boards 95 are slidable in a different plane than the plane of movement of the neck board. However, the surfaces 35 of the shank bay extensions slide in the same plane as that of the surfaces 36 of the neck board 27. Furthermore, the front surface 37 of the belly board 29 is in the plane of the surface 36 of the neck board 27, and the surfaces 35 of the shank bay extensions 34.

In stretching a skin, such for example as 105 the skin shown at 38 in Fig. 1, the belly

portion 39 is secured by nails, pins or other suitable means such as shown at 40 to the belly board 29. The shank portions 41 of the skin are secured in similar manner to the shank bay extensions and the neck portion 42 is similarly secured to the neck board 27. The shank boards 31 and 32 can be moved apart and the neck board 27 can be moved downwardly by any suitable means so as 10 to stretch the skin and after said shank boards and neck board have been moved, they can be secured, in the positions into which they have been moved, by inserting the pins 21 and 25 in their respective holes 15 immediately adjacent the top edge of the neck board and the inner edges of the shank boards, as clearly shown in Fig. 7.

By arranging the holes in the upper and lower beams and uprights in a staggered 20 formation as illustrated, it is possible to place the holes a sufficient distance apart to insure sufficient strength of material, but at the same time a very small adjustment 25 can be secured since the pins can be inserted in the holes which are nearest to the above mentioned edges of the shank and neck boards irrespective of the row of holes in which the pins are inserted.

From the foregoing description it will be 30 understood that the spaces 22 and 26 provide slideways respectively for the shank boards and neck board and the blocks 12 and 17 form a separating means to insure a freedom of movement of said shank and 35 neck boards and at the same time the blocks 12 and 17 provide a reinforcement for the respective strips of the beams and uprights to prevent them from springing apart or moving together.

40 While I have described my invention as taking a particular form, it will be understood that the various parts of my invention may be changed without departing from the spirit thereof, and hence I do not limit 45 myself to the precise construction set forth, but consider that I am at liberty to make such changes and alterations as fairly come within the scope of the appended claims.

Having thus described my invention, what

I claim as new and desire to secure by Let- 50 ters Patent is:—

1. A stretching device of the character described including a frame and transversely extending boards slidably connected to said frame and movable in directions 55 transversely to each other, said boards having portions overlapping each other and other portions providing surfaces in the same plane whereby a skin can be secured against said surfaces in their plane; substantially as described.

2. A stretching frame including uprights and beams, said uprights and beams being made up of strips spaced apart to provide slideways, certain of the strips of said beams 65 extending between and being secured to the strips of said uprights; transversely extending boards movable within said slideways; and means for securing said boards in various positions within said slideways, certain 70 of said boards having extensions providing surfaces included in a plane including an outer surface of another of said boards so that material can be secured against said surfaces in their plane; substantially as de- 75 scribed.

3. A stretching frame including uprights and beams, said uprights and beams being made up of strips spaced apart to provide slideways, certain of the strips of said beams 80 extending between and being secured to the strips of said uprights; and a vertically extending board and a horizontally extending board respectively slidable within the slide- 85 ways of said beams and uprights, said vertically slidable board having a stop block thereon for engagement with one of said beams for preventing the downward movement of said vertical board; substantially as 90 described.

In testimony whereof I have signed my name to this specification in the presence of two subscribing witnesses.

HARRY W. THOMPSON.
